UNITED STATES PATENT OFFICE.

JEANNE MARGUERITE BLANCHARD, OF BORDEAUX, FRANCE.

DIAL-MOVING MECHANISM FOR CLOCKS.

1,137,182.

Specification of Letters Patent.

Patented Apr. 27, 1915.

Application filed July 9, 1914. Serial No. 849,949.

To all whom it may concern:

Be it known that I, JEANNE MARGUERITE BLANCHARD, a citizen of the French Republic, residing at Bordeaux, in France, have invented certain new and useful Improvements in Dial-Moving Mechanism for Clocks, of which the following is a specification.

This invention relates to improvements 10 in and relating to dial moving mechanism for clocks of the kind intended to show the hours 1 to 24 of the new notation in normal order. In mechanism for this purpose it is known to form the dial by a circular plate 15 of the diameter of a clock or watch face, which is provided with twelve openings at the positions of the hours of an ordinary dial, and behind this plate to arrange another plate of the same diameter on which 20 are inscribed the 24 hours of the day arranged so that by a movement imparted to it every twelve hours by mechanism operated by the clock movement, one series of twelve hours automatically comes behind 25 the twelve openings formed in the front plate. The back plate remains stationary for twelve hours whereupon the mechanism again shifts it to cause the other series of twelve hours to appear on the dial. The 30 operating mechanism comprises two detents provided with fingers which bear on semi-circular disks arranged on opposite faces of a toothed wheel gearing with a pinion mounted on the shaft of the hour 35 wheel and making one rotation in twenty four hours, the rotary dial being provided with a pin which is pushed in one or other direction to shift said dial every twelve hours by said detents when their respective 40 fingers no longer bear on said disks due to the rotation of the toothed wheel.

The present invention comprises an improved construction of such mechanism which allows its application to existing 45 clocks without modifying their movement.

The present invention is for the purpose of reducing the resistance to the operation of the detents.

Figure 1 is an elevation of the plate carrying the shifting mechanism. Fig. 2 is a partial section showing the extreme positions of the detent operating on the fixed pins of the movable dial. Fig. 3 is a section illustrating mechanism for imparting 55 an axial movement to the rotary dial during the shifting movement.

On the plate 1 is a cam 2 receiving its movement of rotation by the rotation of the pinion on the hour wheel. Two detents 3 and 4 each constituted by jointed levers can 60 pivot on spindles 5 fixed to the plate 1. The ends of these detents rest successively on pins 6 and 7 in a certain order herein-after described. The pins are fixed to the movable dial 8 and each carries a pulley 9 capable of turning freely thereon. These pulleys carry pins 10. On the movable dial 8 is fixed another pin 11 which can move in a slot 12 formed in the plate 1. Two further slots 13 allow of displacing the pulleys 70 9 in the plate 1. Below the opening 12 are arranged two tappets 14 which block the pin 11 at its extreme end positions. These stopping tappets can turn on spindles carried by the plate 1 and are weighted at their 75 ends 15. Two cables movable in flexible sheaths 16 connect the tappets to the pulleys 9. Two stops 17 and 18 one of which is adjustable are placed at each of the ends of the sheath and limit the movement of the 80 cable in its sheath which causes the movements of the cable at each of its extremities to be equal.

The operation is as follows:—At the exact moment of each release the respective detent 85 3 or 4 drops onto the respective pin 7 or 6 which causes the movable dial to move for the required distance, but before reaching the respective pin 7 or 6 the detent meets the pin 10 fixed to the pulley 9. Under the 90 pressure of the detent the pin 10 rotates the pulley 9 on which is wound the end of the cable 16 which transmits the movement to the tappet 14. This traction is for the purpose of raising the counterweight of the tappet 95 14 which drops to free the pin 11 which it has maintained blocked for 12 hours. At this moment the pin 11 fixed to the movable dial being freed moves in the opposite direction while sliding over the other tappet 100 which rises in its turn to again block the movable dial for 12 hours by the pin 11 in its new position. As can be seen the device allows the movement of the pin 11 toward its two extreme positions with the least 105 possible resistance.

It is advisable that the movable dial should be displaceable axially on its axis of rotation at each release that is to say to move away from the fixed dial and again 110 approach it after its turning movement so that the movable dial can normally lie close

against the fixed dial and move away therefrom when the automatic shift takes place so as to prevent resistance due to friction between the two dials.

5 On the front face of the mechanism plate 1 and concentric to the shaft supporting the dials 8, 20 are a number of tracks 21 formed of two parts in projection connected by two declivous parts, the distance between the two 10 summits of the slopes corresponding to the amplitude of the rotary shifting movement of the movable dial at this point of its circumference. The movable dial 8 carries on its rear face a number of teeth 22 respectively coacting with the aforesaid tracks and operating to effect the recoil and advance of the movable dial. Normally each tooth bears on the high part of the respective track, a weak spring 23 arranged between 15 the fixed dial 20 and the movable dial 8 assures this application. At the time when the dial shifts the various teeth move down the slopes on which each one rests and then move up the opposite slope thus causing the 20 dial to move axially, the amount of said axial movement depending on the depth of the inclined parts of the tracks. For clocks having large dials rollers could be provided to eliminate friction.

25 30 What I claim as my invention and desire to secure by Letters Patent of the United States is:—

35 40 1. In dial moving mechanism for clocks, the combination of a fixed dial, a rotary dial coaxial therewith, means for imparting a rotary movement to said rotary dial in a reverse direction every 12 hours, a pin on said rotary dial, two pivoted tappets adapted to be respectively brought into position to prevent movement of said pin and said dial for a definite period and means for operating said tappets.

Copies of this patent may be obtained for five cents each, by addressing the "Commissioner of Patents, Washington, D. C."

2. In dial moving mechanism for clocks the combination of a fixed dial, a rotary dial coaxial therewith, a cam rotated by the 45 clock mechanism, pivoted and jointed detents coacting with said cam at one end and operated thereby, rollers mounted on said movable dial, pins on said rollers upon which the other ends of said detents rest, a pin on 50 said rotary dial, two pivoted tappets adapted to be brought into position to prevent movement of said pin, and said movable dial, and flexible transmission means connecting said rollers with said tappets adapted 55 to move said tappets to engage or release said pin by the movement of said detents.

3. In dial moving mechanism for clocks the combination of a fixed dial, a rotary dial coaxial therewith, a cam rotated by the 60 clock mechanism, pivoted and jointed detents coacting with said cam at one end and operated thereby, rollers mounted on said movable dial, pins on said rollers upon which the other ends of said detents rest, a pin on 65 said rotary dial, two pivoted tappets adapted to be brought into position to prevent movement of said pin and said movable dial, flexible transmission means connecting said rollers with said tappets adapted to move 70 said tappets to engage or release said pin by the movement of said detents, and means for imparting axial movement to said rotary dial so as to bring it away from and back toward said fixed dial during its movement 75 of rotation.

In witness whereof I have signed this specification in the presence of two witnesses.

JEANNE MARGUERITE BLANCHARD.
